UNITED STATES PATENT OFFICE

GEORGE GODDU, OF WINCHESTER, MASSACHUSETTS, ASSIGNOR, BY MESNE ASSIGNMENTS, TO THE LITTLEWAY PROCESS COMPANY, OF BOSTON, MASSACHUSETTS, A CORPORATION OF MASSACHUSETTS

MANUFACTURE OF SHOES

Original application filed July 29, 1927, Serial No. 209,299. Divided and this application filed January 21, 1930. Serial No. 422,452.

This invention relates to the manufacture of shoes, and more particularly to the fastening of uppers to soles or insoles, this application being a division of a copending application, Serial No. 209,299, filed on July 29, 1927. The invention is herein illustrated by reference to the manufacture of shoes of that type in which the margin of the upper is fastened in substantially parallel relation to the shoe bottom on the outer or bottom face of an insole preparatory to the fastening of an outsole directly to the margin of the upper, for example, by through-and-through stitches penetrating both the outsole and the insole. It is to be understood, however, that the invention is not limited to the manufacture of shoes of that particular kind.

In Letters Patent No. 1,742,502, granted upon an earlier application on January 7, 1930, I disclosed and claimed a novel method of fastening uppers to insoles by the use of fastenings, shown as staples, anchored within the body of the insole instead of by clinching them on any surface of the work. More particularly, in accordance with that disclosure, the legs of each staple were deflected in planes transverse to the cross-bar in the driving operation, by engaging them at the same side of the work from which the staple was driven, to cause them to follow curved paths in the insole. The present invention provides a method of fastening uppers by fastenings anchored by curvature in the same general manner as disclosed in the above-mentioned Letters Patent, and so applied in relation to the shoe as to afford particularly effective insurance that the upper will be held securely in place. More particularly, as herein illustrated, the margin of the upper is fastened by driving staples through it and into the insole with their cross-bars extending lengthwise of the edge of the insole and by so deflecting the staple legs as to cause them to follow curved paths leading inwardly away from the edge of the insole to anchor them. With each staple driven and anchored in this relation to the shoe, any pull of the margin of the upper thereon, in a direction outwardly toward the edge of the insole, only tends to turn the staple about the axis of curvature

of its legs in the same direction in which the legs were deflected in the insole, so that special insurance is afforded that the upper will be held securely in place. Preferably, as illustrated, each fastening or staple is driven by force applied in a direction inclined outwardly toward the edge of the insole while being deflected or curved as above described.

In addition to its novel method aspects, the invention further presents novelty in a shoe having its upper secured to a sole or insole by fastenings applied as hereinabove described. In addition to the security afforded in the hold of such fastenings upon the upper, a further advantage, in shoes of the through-and-through sewed type, is that the fastenings may be located nearer the edge of the insole, without interfering with the outsole stitches, than if they were deflected or curved outwardly toward the edge of the insole to anchor them.

The invention will now be more particularly described by reference to the accompanying drawings and thereafter pointed out in the claims. The drawings illustrate the practice of the method by the aid of operating instrumentalities which are part of the organization of a side-lasting machine shown and described in the copending application of which this application is a division, but it will be understood that the invention is not dependent upon the use of instrumentalities of that particular character nor limited to the fastening of an upper in the lasting operation.

In the drawings,

Figs. 1, 2 and 3 are views illustrating the practice of the method by reference to different successive positions of the above-mentioned instrumentalities;

Fig. 4 is a view at a different angle, showing the instrumentalities as positioned in Fig. 3 and illustrating more fully the relation between them;

Fig. 5 is a perspective view of a portion of a partially completed shoe the upper of which has been fastened along the sides by the novel method; and

Fig. 6 is a cross-sectional view of a portion of the shoe after the fastening of the outsole

to the upper and insole by through-and-through stitches.

In accordance with the procedure illustrated, a last having an insole *a* and an upper *b* thereon is presented with the upper at or near the edge of the insole in engagement with an edge rest 10 and with the outer or bottom face of the insole in engagement with a sole rest 12, and the upper is then pulled heightwise of the last and inwardly over the insole by a gripper 14, as indicated in Fig. 1, after which the margin of the upper is laid inwardly over the insole and pressed upon the outer or bottom face of the latter, as illustrated in Fig. 2, by the action of a staple-guiding nozzle 16 and a staple deflector 18 which for this purpose are moved as a unit in a direction inclined downwardly toward the outer face of the insole and inwardly away from the edge of the insole. While the upper is thus held with its margin in substantially parallel relation to the outer face of the insole, after its release by the gripper, it is fastened in accordance with the method of this invention. For this purpose a staple having initially straight legs is driven from the nozzle 16 by a driver 20 which is moved in a direction inclined downwardly and outwardly toward the edge of the insole, or outwardly toward that side of the shoe which is nearest to the fastening point. The staple is thus driven with its cross-bar extending lengthwise of the edge of the insole, as illustrated in substantially parallel relation to the edge, and as it is driven its legs are engaged and deflected by the deflector 18, the lower end of which occupies a position opposite the end of the staple-guiding passage in the nozzle 16 for engaging the staple legs at the same side of the work from which the staple is driven, i. e., without the presence of any portion of the work between the nozzle and the deflector. The deflector 18 is provided with grooves, one of which is shown in dotted lines at 22 (Fig. 1), for guiding and deflecting the staple legs in planes transverse to the cross-bar, and different portions of the legs are thus deflected or curved successively in the driving operation before the different respective portions enter the shoe. It will be observed that, while the staple is driven by force applied in a direction inclined outwardly toward the edge of the insole as hereinbefore described, the staple legs are deflected in such paths that they enter the shoe in directions approximately perpendicular to the outer face of the insole and then follow curved paths leading inwardly away from the edge of the insole, the degree of curvature of the legs being preferably such that their ends return toward the outer face of the insole without penetrating its inner face. It will thus be seen that the legs of the staple are curved substantially throughout their lengths, and that after the staple has been driven the ends of

the legs are located farther inwardly from the edge of the insole than the cross-bar.

It will be understood that the operations described will be performed successively in different locations along the sides of the shoe. With the staples driven and anchored in the manner and in the relation to the shoe herein disclosed, especially effective insurance is afforded that they will maintain a firm hold upon the upper, since any pull or strain of the margin of the upper thereon in a direction outwardly toward the edge of the insole only tends to turn each staple about the axis of curvature of its legs in the same direction in which the legs were deflected or curved in the driving operation.

As hereinbefore suggested, the method of the present invention is not dependent for its utility upon the pulling of the upper as an accompaniment to the upper-fastening operation, but is applicable to the driving and anchoring of upper-securing fastenings independently of any other operation, as sometimes required in shoe manufacture and as also provided for in the machine organization disclosed in the copending application of which this application is a division.

Fig. 6 illustrates, in a shoe of the through-and-through sewed type, the relation of the staples *s*, driven and anchored as hereinbefore described, to the seam *t* whereby the outsole *c* is secured to the upper and insole. It will be evident that when the staples are driven and anchored as illustrated, in addition to other advantages above mentioned they may be so applied that their cross-bars engage the upper in locations nearer the edge of the insole, without danger that their legs will interfere with the outsole stitches, than if the legs were deflected outwardly toward the edge of the insole to anchor them.

While the invention is illustrated and described with particular reference to the manufacture of shoes having an outsole and an insole in the relation disclosed, the invention in various aspects, as hereinbefore stated, is not limited in utility to the manufacture of shoes of that particular type, and the term "sole" is accordingly used in many of the claims in a comprehensive sense to include both the insole of some types of shoes and also that part which in shoes of other types may be the outsole or the only sole with which the shoe is provided. It is to be further understood that in the claims the expression "edge of the sole" is used for convenience to designate that portion of the edge which is nearest to the location where the fastening is inserted, and that the expression "bottom face of the sole" is used with reference to that face which is outermost at the time of the upper-fastening operation, regardless of its position in the completed shoe.

The method of lasting herein disclosed is claimed in another divisional application Ser.

rial No. 422,454 filed on Jan. 21, 1930; and the lasting means in still another divisional application Serial No. 422,453 filed on Jan. 21, 1930.

Having described the invention, what I claim as new and desire to secure by Letters Patent of the United States is:

1. That improvement in methods of fastening an upper to a sole which consists in driving a metallic fastening through the upper and into the sole by force applied in a direction inclined outwardly toward the edge of the sole, and by engaging the fastening in the driving operation at the same side of the work from which it is driven deflecting it progressively in a curved path leading inwardly away from the edge of the sole to anchor it.

2. That improvement in methods of fastening an upper to a sole on a face of the sole parallel to the shoe bottom which consists in driving a fastening by force applied over said face in a direction outward toward the edge of the sole, and by engaging the fastening in the driving operation at the same side of the work from which it is driven deflecting it into the upper and the sole in a path such that its entering end is displaced farther inwardly from the edge of the sole than its upper-engaging portion.

3. That improvement in methods of fastening an upper to a sole which consists in driving a fastening through the upper and into the sole at a distance from the edge of the sole, and, in the driving operation, curving substantially all portions of the fastening that enter the shoe in such relation to the edge of the sole that the portions of the fastening in the sole follow a course leading inwardly away from said edge.

4. That improvement in methods of fastening an upper to a sole on a face of the sole parallel to the shoe bottom which consists in applying to the upper and the sole a fastening extending through the upper and said face and curved substantially throughout its length in the shoe materials in such relation to the edge of the sole that its entering end is displaced farther inwardly from said edge than its upper-engaging portion.

5. That improvement in methods of fastening an upper to a sole which consists in driving a staple through the upper and into the sole with its cross-bar extending lengthwise of the edge of the sole, and, in the driving operation, deflecting the legs of the staple substantially throughout their lengths in curved paths leading inwardly away from the edge of the sole to anchor them.

6. That improvement in methods of fastening an upper over the bottom face of a sole to hold it against outward strain toward the edge of the sole which consists in applying to the upper and the sole a staple with its cross-bar extending in substantially parallel

relation to the edge of the sole and its legs curved substantially throughout their lengths in paths leading inwardly away from said edge to anchor them in the body of the sole.

7. That improvement in methods of fastening an upper to a sole which consists in driving a staple through the upper and into the sole by force applied in a direction inclined outwardly toward the edge of the sole with the cross-bar of the staple extending lengthwise of said edge, and by engaging different portions of the legs of the staple successively in the driving operation, before the different respective portions enter the sole, deflecting them in curved paths leading inwardly away from the edge of the sole to anchor them.

8. That improvement in methods of fastening an upper to a sole on a face of the sole parallel to the shoe bottom which consists in driving a staple through the upper and said face with the cross-bar of the staple extending lengthwise of the edge of the sole, and by engaging the legs of the staple in the driving operation at the same side of the work from which the staple is driven deflecting them progressively in curved paths leading inwardly away from the edge of the sole and reversely toward said face to anchor them.

9. That improvement in methods of fastening an upper to a sole on a face of the sole parallel to the shoe bottom which consists in applying to the upper and the sole a staple with its cross-bar extending lengthwise of the edge of the sole in engagement with the upper and its legs curved substantially throughout their lengths in the shoe materials in such relation to the edge of the sole that the ends of said legs are displaced farther inwardly from said edge than the cross-bar.

10. That improvement in methods of fastening an upper over the bottom face of a sole which consists in driving a staple through the upper and into the sole, and by engaging the legs of the staple in the driving operation at the same side of the work from which the staple is driven deflecting the staple legs in curved paths such that the ends of the legs follow in the sole a course leading inwardly away from the edge of the sole.

11. That improvement in methods of fastening an upper over the bottom face of a sole which consists in driving a staple by force applied over said face in a direction outward toward the edge of the sole with the cross-bar of the staple extending lengthwise of said edge, and by engaging the legs of the staple in the driving operation at the same side of the work from which the staple is driven deflecting them into the upper and the sole in curved paths such that the ends of the legs follow in the sole a course leading inwardly away from the edge of the sole.

12. A shoe having its upper fastened over the outer face of a sole by fastenings extending through the upper and said face and curved substantially throughout their lengths in the shoe materials in such paths that their ends are displaced farther inwardly from the edge of the sole than their upper-engaging portions.

13. A shoe having its upper fastened to a sole on a face of the sole parallel to the shoe bottom by fastenings extending through the upper and said face and curved from the points where they enter the sole in such relation to the edge of the sole that their ends are displaced farther inwardly from said edge than their upper-engaging portions.

14. A shoe having its upper fastened to a sole on a face of the sole parallel to the shoe bottom by fastenings extending through the upper and said face, but only part way through the sole, and curved within the body of the sole in such directions that their ends are displaced farther inwardly from the edge of the sole than their upper-engaging portions.

15. A shoe having its upper fastened to a sole by staples arranged with their cross-bars extending lengthwise of the edge of the sole and with their legs curved substantially throughout their lengths in paths leading inwardly away from the edge of the sole to anchor them in the sole.

16. A shoe having its upper fastened to the outer face of a sole by staples arranged with their cross-bars extending lengthwise of the edge of the sole in engagement with the upper and with their legs anchored within the body of the sole by curvature thereof in paths leading inwardly away from the edge and reversely toward the outer face of the sole.

17. A shoe having its upper fastened to a sole on a face of the sole parallel to the shoe bottom by staples arranged with their cross-bars extending lengthwise of the edge of the sole in engagement with the upper and with their legs extending through the upper and said face and curved from the points where they enter the sole in such relation to the edge of the sole that the ends of the legs are displaced farther inwardly from said edge than the cross-bars.

18. A shoe having its upper fastened to the outer face of an insole by staples arranged with their cross-bars extending lengthwise of the edge of the insole and their legs curved substantially throughout their lengths in the shoe materials in paths leading inwardly away from the edge of the insole, the staples being so positioned as to permit an outsole to be secured to the upper and insole by through-and-through stitches located between the staples and the edge of the insole.

In testimony whereof I have signed my name to this specification.

GEORGE GODDU.
